UNITED STATES PATENT OFFICE.

JOSEPH W. MOORE, OF DES MOINES, IOWA.

BLOCK WALL-PAPER TRIMMER.

No. 920,980.

Specification of Letters Patent. Patented May 11, 1909.

Application filed November 23, 1908. Serial No. 463,977.

To all whom it may concern:

Be it known that I, JOSEPH W. MOORE, a citizen of the United States, residing in Des Moines, county of Polk, and State of Iowa, have invented a new and useful Improvement in Block Wall-Paper Trimmers, of which the following is a specification.

The object of my invention is to provide a trimmer or cutter, designed to operate in conjunction with a straight edge, and adapted for use in trimming wall paper, carpet, linoleum or other like articles.

My main object is to provide a trimmer, of this class, which will operate on any straight edge without it being necessary to prepare the straight edge to receive the device, and in this way any ordinary board, rule, or the like, may be utilized.

Another object is to provide such a device in a simple, strong, durable and practically inexpensive construction.

My invention consists of certain details of construction, hereinafter set forth, pointed out in my claims and illustrated in the accompanying drawings, and in which:

Figure I shows a side elevation view of my device; Fig. II shows a longitudinal sectional view of the same; Fig. III shows a transverse sectional view of the same; and Figs. IV, V and VI are detail views of parts of my device.

Referring to the accompanying drawings, the reference numeral 10 is used to indicate the body of my trimmer, said body being dome shaped in conformation and hollowed 35 on the inside as shown. One longitudinal side of the said dome shaped body portion is provided with a depression 11, and in this depression the cutting wheel 12 is designed to operate. The cutting wheel 12 is secured 40 to a shaft 13, which projects through an oblong and slightly curved orifice 14, to the opposite longitudinal side of the dome, where it is mounted in an oblong and slightly curved slot 15. The orifice 14 and the slot 15 are 45 alike in conformation, and are designed to act as companions in receiving the shaft, and the shaft is designed for upward and downward movement therein.

The numeral 16 indicates a plate secured 50 to the longitudinal side of the body portion, and designed to cover the outer surface of the cutting wheel, or a portion thereof as shown, this plate being designed to protect the hand of the operator. Mounted in the 55 sides of the dome shaped body portion and

near one end thereof, is a second shaft 16^a, and this shaft is parallel to the shaft 13.

The numeral 17, indicates a collar or ferrule, through which the shaft 13 is threaded, and projecting rearwardly from said ferrule is a lug 18, which is secured for pivotal movement to the shaft 16. Projecting upwardly from the central portion of the said ferrule 17, are a pair of ears 19, designed as a mounting for an upwardly extending vertical shaft 20, 60 the said shaft being loosely secured thereto. The upper portion of said shaft 20, extends centrally through the top of the dome shaped body portion, and is provided with a head 21.

The numeral 22 indicates a coil spring, 70 mounted on the shaft 20 and secured to the body portion in such a manner as to cause the normal position of the shaft 20, to be at its upward limit of movement. The ferrule 17 is provided with ball-bearings, designed to 75 engage the shaft 13. The numeral 23 indicates a second coil spring, mounted between the side of the body portion opposite the cutting wheel and the end of the ferrule 17, said spring engaging, and mounted upon, 80 the shaft 13.

Numerals 24 and 25 indicate strengthening shafts secured near the base of the dome shaped body portion.

The numeral 26, indicates a flange, 85 projecting from the body portion on the side opposite to the cutting wheel, and this flange is designed to project downwardly and engage the surface of the straight edge.

In practical operation any board, strip of 90 steel, or the like, which has any thickness what-so-ever, and is provided with a straight edge, may be laid upon the article sought to be cut, and my device placed thereon, the flange engaging the straight edge. The 95 operator then presses downward on the head 21, and thus causes the shaft 13 to be lowered, moving downwardly in a radial movement from the shaft 16^a. As the shaft 13 moves downwardly, it causes the cutting wheel 12 to be forced downwardly, and whatever pressure is needed to cut the article described 100 may be applied. It is obvious that various sizes of cutting wheels may be mounted on the shaft 13, and operated in connection with 105 my device.

Having thus described my invention, what I claim, and desire to secure by Letters Patent of the United States, is:

1. A block trimmer comprising in combi-

nation, a body portion and a flange thereon; a horizontal shaft mounted for upward and downward movement in said body portion one end projecting therethrough; a cutting wheel on said projecting end; a second horizontal shaft; a member connecting said horizontal shafts and loosely mounted to each; a vertical shaft extending upwardly from said first horizontal shaft, and extending through 10 the body portion; a head on the upper end of said vertical shaft, substantially as shown and described.

2. A block trimmer comprising in combination, a body portion, and a flange thereon; 15 a depression in one longitudinal side thereof; a cutting wheel mounted in said depression and secured to a shaft, horizontally mounted

for upward and downward movement in the sides of said body portion; a ferrule mounted on said shaft and ball-bearings in said ferrule; a second horizontal shaft and a member connecting said shaft to said ferrule; a vertical shaft extending upwardly from said ferrule through the body portion and a head on the upper end of said shaft; a coil spring on said vertical shaft; a second coil spring between the first mentioned horizontal shaft and the side of the body portion, all arranged and combined, substantially as shown and described.

JOSEPH W. MOORE.
